ANTENNA SELECTOR

John B. Moore, Riverhead, N. Y., assignor to
Radio Corporation of America, a corporation
of Delaware

Application November 16, 1928, Serial No. 319,768

12 Claims. (Cl. 250—20)

This invention relates to diversity reception, and more particularly to a method and means for selecting from a plurality of antennas that antenna which is supplying the strongest signal.

5 Short wave signals are subject to fading which varies both in frequency and degree in an unpredictable manner. Inasmuch as the fading at any instant may differ very widely at geographically spaced points, or in different planes of polarization, it has been suggested that a receiving 10 station be equipped with a number of antennas having different fading characteristics, the energies collected by which are fed to a single signal responsive means.

15 Experience has shown that high frequency energy fluctuates not only in intensity but also in phase, and that there may be considerable relative phase fluctuation on the different antennas. This phenomenon makes it impossible to directly 20 combine the audio frequency energies, for the energies may as often be in phase opposition as in like phase. To overcome this difficulty it has been suggested to equip each of the antennas with a separate receiver, and to combine the 25 energies only after rectification, and this, in the case of code signals, has proven an apt solution.

30 However, I have found that in the case of speech telephony, or other speech-simulating signals, where the transmission energy is radiated in the form of a carrier and side bands, there is a relative difference in the phase fluctuations of closely adjacent frequencies, such as side band and carrier frequencies, even at one antenna, just as there is between carriers of like frequency at different antennas. This causes similar phase fluctuations in the beat of the carrier and side bands, for if of two beating waves one is kept constant in phase, while the other is shifted in phase, their 35 beat is equally shifted in phase.

40 This may readily be understood by visualizing two beating radio frequency waves of slightly different frequency, which have an envelope which is a maximum where the waves are cophasal, and which gradually drops off to a minimum where the waves are in phase opposition. Now if the phase of one of these waves is kept constant while the phase of the other is shifted 45 180 degrees the waves will be in phase opposition where before they were cophasal, so that the envelope will be a minimum where before it was a maximum, and where the waves were in phase opposition they now will be cophasal, so that the envelope will be a maximum where before it was a minimum, and, therefore, in effect the envelope 50 too has been shifted 180 degrees in phase.

Because of the foregoing considerations it follows that although the carrier and side band energies experience only radio frequency differences in phase, these differences are transferred to the detected or audio frequency energies, so that it 5 is as impossible to combine the detected energies as it is to directly combine the originally collected radio frequency energies.

The primary object of my invention is to overcome this difficulty, making possible the application of diversity reception to overcome fading of speech-simulating signals, and for this purpose I collect signal energy on a plurality of antennas so geographically spaced, or so altered in plane of polarization, or otherwise changed, that the 15 fading characteristics thereat usually differ, as heretofore, but I then feed the collected energy to a receiver from only that point of collection or antenna at which the collected energy is a maximum, instead of from all of the antennas at 20 once.

With the usual type of diversity system, even if applied merely to code signals, the received energy is apt to vary between the extremes of almost complete fading at all of the antennas 25 to no fading at any of the antennas. To overcome this it has been suggested to employ a volume control with each antenna for varying the gain in the amplifier coupled thereto. Such an arrangement suffers from the disadvantage 30 that the increased gain given an amplifier of an antenna at which fading is prevalent increases the noise level in the output of that amplifier, and therefore in the combined output of the entire system. Furthermore, in the case 35 of speech-simulating signals, in the event of fading of the carrier and not of the side bands at an antenna its amplifier is given increased gain, as a result of which the beat between the side bands is unduly amplified before being combined 40 with the output from the other antennas, thereby creating augmented distortion.

To overcome the foregoing difficulties is a further object of my invention, which I fulfill by the process which I have already suggested, 45 namely, feeding the collected energy to the receiver from only one of the antennas at a time. This inherently provides considerable volume control, for the condition of no fading at any of the antennas does not create a powerful signal 50 equal to the integral of the several signals, because only one instead of all of the antennas is connected to the receiver. Furthermore, among all of the several antennas employed there is almost always one having a fairly strong signal, 55

and the automatic coupling of the receiver to this antenna amounts, practically, to automatic volume control.

To provide volume control within still narrower limits, so as to obviate the effect of partial fading of even the maximum signal, I combine automatic volume control with the receiving system which I have already described.

My invention is more completely described in the following specification which is accompanied by drawings in which Figure 1 is a wiring diagram for an arrangement with two antennas; and Figure 2 is an arrangement employing a greater number of antennas.

Referring to Figure 1 there are two geographically spaced antennas 2 and 4, which are coupled by transmission lines 6 and 8 to radio frequency amplifiers 10 and 12. The output from these amplifiers is fed to means to heterodyne the received radio frequency energy to energy of intermediate frequency, indicated by the rectangles 14 and 16, and which may comprise separate oscillators and heterodyne detectors, or autodyne circuits in which the same tube acts as an oscillator tube and as a heterodyne detector tube. The intermediate frequency is amplified in suitable intermediate frequency amplifiers 18 and 20, the amplified outputs from which are detected in detector tubes 22 and 24, across the anode circuits of which there are connected the filter sections 26 and 28 for by-passing the radio frequency components of the rectified energy. The remainder of the anode to ground circuit includes sources of direct anode potential 30 and 32 and volume control impedances 34 and 36. The potential across the impedance 34 is applied through the leads 38 and 40 to the control electrodes of the tubes in the amplifiers 10 and 18, and also, by way of the leads 38 and 42, to the control electrode of the tube 44 of the pair of tubes 44 and 46. The potential across the impedance 36 is applied by way of leads 48 and 50 to the control electrodes of the vacuum tubes in the amplifiers 12 and 20, and also, through the leads 48 and 52, to the control electrode of the tube 46. The resistances 39 and 49 are provided in series with the condensers 37 and 47 in order to form electrically slow circuits for volume control and antenna selection. By a proper choice of the magnitudes of the resistance and capacitance the time constant of the volume control and relay selector response may be made of desired value. The normal bias on the control electrodes of the tubes 44 and 46 may be adjusted by the means of the potentiometer resistances in parallel with the bias batteries, as shown.

The differential of the anode currents of the tubes 44 and 46 depends upon the differential of the potentials on their control electrodes, which in turn depends upon the potentials across the impedances 34 and 36, which, of course, vary in accordance with the strength of the signals received by the antennas 2 and 4. The differential of the anode currents may be applied directly to the coils of a differential relay, the armature of which is arranged to act as a switch to connect a utilization circuit to that one of the impedances 34 and 36 through which the greater signal energy is flowing. However, in such case the relay would have to accommodate itself to wide ranges in variation of current, and therefore could not be quite so sensitive as the arrangement which I prefer to employ and which is next described, but it should be understood that either arrangement is

responsive to the differential of the anode currents, the one directly, and the other indirectly. The anodes of the tubes 44 and 46 are coupled to anode impedances 78 and 72, to the junction of which a source of anode potential 74 is connected. The differential of the anode potentials is applied to the input circuit of a tube 76, and the coupling may include a resistance 79 to prevent the flow of appreciable grid current in tube 76 should the anode of tube 44 become considerably more positive than that of tube 46, and to give a more nearly definite maximum to the anode current flow in tube 76, which in general depends upon the differential of the anode potentials of the tubes 44 and 46, and which is utilized in the coil 80 of a differential relay 82. A constant flow of current from a source 84, nicely adjusted by a resistance 86, is fed through the opposed coil 88 of the relay. The adjustments are made such that with equal signal strength on antennas 2 and 4 the current through the relay coil 80 counteracts that through the relay coil 88, but the construction of the relay is such that it will then rest at either contact with equal facility, but will not so centralize itself as to open circuit both contacts. 25

It will be understood that not only might the relay 82 be connected directly in the anode circuits of the tubes 44 and 46, but also the arrangement just described, including the tube 76 and the source 84, might be connected so that the differential of the potentials across the impedances 34 and 36 is applied directly to the control electrode of the tube 76 without the intermediate use of the pushpull tubes 44 and 46, but these are desirable because the voltage amplification obtained by their use permits the relay to function on a very small difference in signal level, which makes the change over imperceptible to the listener. 30

In order to abstract signal energy for utilization there are coupled to the impedances 34 and 36 amplifier tubes 90 and 92, through grid bias blocking condensers 94 and 96. The anode circuits of these tubes include the coupling transformers 98 and 100, the primaries of which are connected together and to a source of anode potential 102. One terminal of the secondaries of the transformers 98 and 100 are connected together and to the primary of transformer 104, while the other terminals are led separately to the opposite contacts of the relay 82, as shown. The armature of the relay is then connected to the opposite terminal of the primary of the transformer 104, so that the relay, in contacting with one side or the other, effectively couples either of the amplifier tubes 90 and 92 to the transformer 104. The secondary of the transformer 104 may be the input coil of a pushpull amplifier stage 106, the output from which is fed over a line 108 to acoustic or picture translating means, or a re-broadcasting station, or other suitable means to utilize the signal energy. 50

In the foregoing arrangement it should be understood that the receivers need not be heterodyne receivers, as shown, and that if they are heterodyne receivers, the volume control leads 40 and 50 may be connected to either the high frequency or the intermediate frequency amplifiers alone, as well as to both, as shown, and that, furthermore, volume control leads 40 and 50 are not at all essential to the practice of the invention in its broadest aspect, involving merely antenna selection, though volume control is a useful auxiliary in practice. 65

If it is desired to employ more than two antennas, and at the same time to retain the use of 75

simple double contacting mechanical relays, the arrangement may comprise a plurality of antennas having different fading characteristics, a plurality of detectors coupled thereto, differential relays to select the greater energy of the energies collected by the antennas considered two at a time, differential relays to select the greater of the selected energies, and so on, until the maximum energy has been selected for utilization.

Such an arrangement, as applied to three antennas, is indicated in Figure 2, in which there are a plurality of antennas 110, 112 and 114, either geographically spaced, or in different planes of polarization, or otherwise given different fading characteristics, which are coupled by means of transmission lines 120, 122 and 124, to receiving sets 130, 132, and 134, as shown. The rectified output from receivers 130 and 132 is applied to a differential relay selector 136, while the rectified outputs from the receivers 132 and 134 are fed to another differential relay selector 138. The volume of energy from receivers 130 and 134 is yet to be compared, and these are applied to a third differential relay selector 140, the contacts of which are connected, as shown, to the armature of the relays 136 and 138, the contacts of which in turn are connected to the signal outputs from the various receivers 130, 132 and 134. Inasmuch as these outputs are preferably taken through separate amplifiers, they have been indicated in Figure 2 as coming from separate rectangles 150, 152 and 154, but it should be understood that these are respectively coupled to the receivers 130, 132 and 134, just as was indicated in Figure 1. Through the operation of the three relays 136, 138 and 140, the armature of the relay 140 is ultimately coupled, through intermediate circuits, of course, to that antenna having the strongest signal, and this is then connected, along with the common lead 156 from the signal amplifiers 150, 152 and 154, to a line 158, intermediate through a further amplifier 160, should this prove desirable. As before, the line 158 is led to any suitable utilization means.

I claim:

1. The method of reception which includes collecting signal energy on three geographically spaced antennas, separately rectifying the collected signal energies, comparing the rectified energies obtained from two of the antennas and selecting the greater, comparing the rectified energies obtained from another two of the antennas and selecting the greater, comparing the rectified energies from the remaining two and using them to select the greater of the selected energies, and utilizing the finally selected energy.

2. The method of reception which includes collecting the received energy on a plurality of geographically spaced antennas, separately amplifying the received energies, separately rectifying the amplified energies, controlling the gain in the aforesaid step of amplification in response to the volume of the rectified energies to obviate the effect of partial fading, and selecting the maximum of the rectified energies for utilization.

3. A receiving system for the reduction of fading of high frequency signals comprising a plurality of antennae so geographically spaced that the fading characteristics thereat usually differ, means individual to each antenna for automatically volume controlling energies derived therefrom, a receiver, and automatic switching means responsive to the differential of the volume controlled energies collected on the antennas for cou-

pling the receiver to that antenna only at which the collected energy is a maximum.

4. A diversity receiving system for overcoming the effect of fading of speech-simulating signals transmitted on a high frequency carrier, in spite of fluctuations in the relative phase of closely adjacent frequencies such as side band and carrier frequencies, comprising a plurality of antennas having different fading characteristics, means individual to each antenna to volume control the energy collected on each antenna, a receiver, and differential relay switching means responsive to the differential of the volume controlled energies derived from energies collected by the antennas for coupling the receiver to that antenna only at which the received signal is strongest.

5. A receiving system comprising a plurality of antennas of relatively different fading characteristics, a plurality of detectors coupled thereto, means individual to each antenna to automatically volume control energies collected thereby, a utilization circuit, and switching means responsive to the differential of the detected automatically volume controlled energies for coupling the utilization circuit to that detector at which the rectified automatically volume controlled energy is a maximum.

6. A receiving system comprising a plurality of geographically spaced antennas, a plurality of detectors coupled thereto, means individual to each antenna circuit for automatically volume controlling energies collected thereon, a utilization circuit, and switching means responsive to the differential of the detected automatically volume controlled energies for coupling the utilization circuit to that detector at which the automatically volume controlled rectified energy is a maximum.

7. A receiving system comprising a plurality of geographically spaced antennas, a plurality of detectors coupled thereto, means to select the greater energy of the energies collected by the antennas considered two at a time, means to select the greater of the selected energies, until the maximum energy has been selected, and means to utilize the maximum energy.

8. A receiving system comprising three geographically spaced antennas, a plurality of detectors coupled thereto, means to compare the detected energies obtained from two of the antennas and to select the greater, means to compare the detected energies obtained from another two of the antennas and to select the greater, means to compare the detected energies from the remaining two antennas and to utilize them to select the greater of the selected energies, and means to utilize the finally selected energy.

9. A receiving system comprising a plurality of geographically spaced antennas, means to separately amplify the collected energies, means to separately rectify the amplified energies, volume control means for controlling the gain in the amplifiers in response to the volume of the rectified energies in order to obviate the effect of partial fading, and means to select the maximum rectified energy for utilization.

10. A receiving system comprising a plurality of geographically spaced antennas, means to separately rectify the energies collected thereby, an impedance in each of the detector circuits, a pair of electron emission tubes, means to apply the potential caused by the flow of the rectified currents through said impedances to the control electrodes of the pair of tubes, means to combine the anode currents of the tubes differen-

tially, a utilization circuit, and a differential relay responsive to the differential of the anode currents for connecting the utilization circuit to that detector circuit through which the maximum signal energy is flowing.

11. A receiving system comprising a plurality of geographically spaced antennas, a plurality of amplifiers coupled thereto, a plurality of detectors coupled to the amplifiers, an impedance 10 in each of the detector circuits, a pair of electron emission tubes, means to apply the potential drop across the impedances to the control electrodes of the amplifier tubes in order to control the gain therein and to the control electrodes of the pair of electron emission tubes, means to combine the anode currents of the pair of tubes differentially, a utilization circuit, and a differential relay responsive to the differential of the anode currents for connecting the utilization

circuit to that detector circuit having the maximum signal energy.

12. A receiving system comprising a pair of geographically spaced antennas, a detector coupled to each of said antennas, an impedance in each of the detector circuits, a pair of electron emission tubes, means to apply the potential drops across the impedances to the control electrodes of the tubes, means coupling the anode circuits of the tubes differentially and to the control 10 electrode of a third tube, a differential relay, means coupling one of the coils of the relay to the anode circuit of the third tube, a source of constant current for the other coil of the relay, a utilization circuit, and a switch actuated by the relay for coupling the utilization circuit to that detector impedance across which the potential drop is greater. 5

JOHN B. MOORE.
